COLLAPSIBLE STAND

Roy L. Stover, Wichita, Kans., assignor, by mesne assignments, to Kay-Win Products Company, Wichita, Kans., a corporation of Kansas

Application July 19, 1946, Serial No. 687,343

1 Claim. (Cl. 211—172)

1

This invention relates to improvements in collapsible stands which have horizontally-extending supporting arms from which articles may be suspended. More particularly this invention relates to stands wherein the legs can be folded up to extend substantially coaxially with the central support of the stand while the supporting arms can be rotated until they are coaxial with the central support of the stand and then telescoped within that support.

It is an object of the present invention to provide an improved collapsible stand, from the arms of which articles may be suspended.

In my co-pending application Serial No. 629,601 entitled Collapsible Stands and filed November 19, 1945, there is disclosed a tubular central support which has three legs hinged to one end thereof and has a slotted head secured to the other end thereof. That collapsible stand has proved to be of great value and has received wide commercial acceptance. With that stand the legs can all be rotated until they are substantially coaxial with the central support of the stand; and then the ends of the legs, which are bent relative to the axes of the legs, can be made to enter slots formed in the upper end of the central support. Thereafter a spring-biased sleeve which is slidably secured to the central support can be moved down over the outer edges of the free ends of the legs to hold those legs in assembled relation with the central support. The supporting arms of that stand are provided with transversely-extending pins or transversely-projecting ears at the ends thereof; and these arms are threaded through the slotted head member in such a manner that they can be telescoped into the tubular central support or can be drawn outwardly of that support until the transversely-extending pins or ears strike and are held by the slotted head member. Thereafter the arms can be rotated into, and held in, a horizontal position and in that position the arms can be used to support articles that are to be suspended from the collapsible stand. While that stand is extremely useful and has met wide acceptance, I have devised improvements therefor that additionally increase its utility and value. For example I have found that by changing the configuration of the spring-biased collar on the central support I can eliminate the necessity of having the free ends of the legs angularly disposed relative to the axes of the legs. Accordingly I can use legs that are of generally straight configuration. By using legs of generally straight configuration I not only decrease the cost of the legs

2

but I avoid the presence of open slots in the wall of the central support, which slots were formerly believed necessary to permit the maintenance of the legs in substantially coaxial relation with the central support. In this way I not only decrease the cost of manufacture of the collapsible stand of my co-pending application, but I also improve the appearance and strength of the stand by eliminating the open slots that were previously formed in the upper wall of the central support of that stand.

In addition I have discovered that it is possible to mount the slotted head of the collapsible stand of my co-pending application so that it can rotate relative to the central support of the collapsible stand without becoming separated from that support. The rotation of the head relative to the central support permits the horizontally-disposed arms to be rotated to any desired position without moving the legs of the stand. This permits the user to set the stand in a corner of a room and add articles to each of the outstretched arms merely by rotating the slotted head of the stand; and it also permits the user to set the stand by the ironing board and unload or load each of the arms of the stand without moving the legs of the stand.

Furthermore I have found it possible to provide a disc of resilient material that can be secured to the slotted head at the approximate center of that head, and to dimension that centrally-disposed disc of resilient material so that it bears against the ends of each and every one of the arms of the stand. Such a disc provides a sufficiently large frictional force between the arms of the stand and the stand itself to retain the arms telescoped within the central support even though the stand is inverted. Thus I keep the arms from dropping outwardly from the central support, under the influence of gravity, when the stand is inverted. It is not intended to infer that the arms of the stand of my co-pending application would fall completely out of the central support because they would not, since the ends of those arms have transversely extending pins secured thereto that prevent removal of the arms from the slotted head. However the arms could, when the stand was inverted, telescope out of the central support until the transversely extending pins carried thereby struck, and were held by, the slotted head. This is prevented in the present invention and makes my collapsible stand even more desirable. It is therefore an object of the present invention to provide a collapsible stand that has generally straight legs hinged adjacent

one end of the central support and also has a flared collar that cooperates with the ends of the legs to maintain those legs in substantially coaxial relation with the central support when the stand is collapsed for shipment, storing or carrying.

It is a further object of the present invention to provide a slotted head for the collapsible stand which is permanently secured to, but is rotatable relative to, the central support of a collapsible stand.

It is a still further object of the invention to provide a centrally disposed resilient disc that is carried by the slotted head of a collapsible stand and bears against the telescoping arms of said stand.

Other objects and advantages of the present invention will become apparent from an examination of the drawing and accompanying description.

In the drawing and accompanying description a preferred embodiment of the present invention is disclosed and described but it is to be understood that the preferred embodiment is shown and described for purposes of illustration only and that the invention is not limited by the drawing and accompanying description. Instead the invention will be defined by the appended claim.

In the drawing, Fig. 1 is a partially sectioned side elevational view of the collapsible stand of the present invention as that stand appears in the collapsed position, and

Figure 2 is a perspective view of the stand of the present invention as that stand appears in the extended position.

Referring to the drawing in detail, the numeral 10 denotes the central support of a collapsible stand made in accordance with the principles and teachings of my invention. Formed in one end of the central support 10 are slots 12 and recesses 14 that are separated by body portions 18 of the central support 10. The slots 12 receive the ends of legs 16, while the recesses 14 make it easy to pass rivets 20 through openings in the body portions 18 of the central support 10. By forming openings in the ends of legs 16, by inserting rivets 20 through those openings as well as the openings in the body portions 18, and then by setting the rivets 20, it is possible to hold the legs 16 in assembled relation with the central support 10, while permitting pivoting of the legs 16 about the rivets 20.

The legs 16 have short portions at their pivoted ends that are angularly disposed relative to the axes of the legs, but the remaining lengths of the legs are straight. Accordingly the legs 16 may be said to be of generally straight configuration. The legs 16 are so hinged to the central support 10 that they can be rotated into position coaxially with the central support 10 of the stand as in Fig. 1; and they can also be rotated into the extended position shown in Fig. 2. In the position shown in Fig. 2, the inner faces of the angularly disposed ends of the legs 16 will bear against the bottoms of the slots 12 while the outer faces of those ends will be held by the flared end of the collar 22. Thus the legs 16 will be fixedly held against further rotation.

The flared collar 22 is normally pressed downwardly by the helical spring 24 and its flared end, can, as indicated in Fig. 1, telescope over the ends of the legs 16 and serve to hold the legs 16 in position while the stand is being shipped, stored or carried. The collar can also be moved downwardly to assume the position shown in Fig. 2.

In that position gravitational and frictional forces hold the collar in position. The collar is provided with rib-portions 23 that are adapted to engage the outer surfaces of the upper ends of the legs 16 and hold the collar 22 against rotation.

Mounted on the upper end of the central support 10 of the collapsible stand, is a grooved head 26. This head has a number of peripherally spaced slots 28 that project radially outward from the solid center of the head 26 and normally receive the arms 30 of the collapsible stand. The arms 30 of the collapsible stand are provided with transversely extending projections 31, that may be made by striking the edge of the arms with a forming tool, and that will not pass through the slots 28 of the head member 26. Accordingly when the stand is once assembled, the arms 30 cannot be removed or separated from the stand. In addition the arms are provided with notches that bear against the upper end of the cavity 32 and limit the rotation of the arms 30.

The head 26 has a generally cylindrical cavity 32 which has an inner diameter slightly larger than the outer diameter of the central support 10, and this cavity permits the head member 26 to telescope over the upper end of the central support 10. Formed in the inner surface of the cavity 32 is a recess 34 of annular form. Projecting from the wall of the central support 10 are two lugs 36 that project outwardly and downwardly from the upper end of the support 10. By making the central support 10 of relatively flexible metal and by punching or otherwise forming the lugs 36 from the wall of the central support 10, I make it possible for the head member 26 to bend the lugs 36 as the member 26 telescopes over the upper end of the support 10. The lugs 36 will be pressed flush with the rest of the sleeve as the member 26 is moved, but thereafter they will spring back into the position shown in Fig. 3; and in that position they fit into the recess 34 and prevent the disengagement of head member 26 from the central support. The lugs 36 are spaced from the upper end of the support 10 a distance sufficient to prevent bending between the upper end of support 10 and the inner end of cavity 32.

Centrally disposed of the rotatable head member 26, and secured thereto by a screw 38, is a resilient disc 40. This disc, which is preferably made of rubber or a resilient plastic material and is preferably made with a circular configuration, is held in position by the screw 38 and it is so dimensioned that its periphery bears against the edges of the arms 30 whenever those arms are retracted within the support 10. Since the disc is of resilient material it does not prevent the user of the stand from moving or rotating the arms 30 relative to the central support 10 or the head 26 but it does prevent accidental movement of arms 30.

The operation of the present invention is as follows. The collapsible stand, which can be placed in the compact position shown in Fig. 1, can be carried in a suitcase, traveling case or any suitable container which will protect it from the elements and from rough handling. Whenever desired, the stand may be removed from its traveling case or other container, the collar 22 can be forced upwardly toward the head 26 against the pressure of the helical spring 24. This upward movement of the collar 22 permits the legs 16 to be rotated away from their position

coaxial with the central support 10, and to be rotated into the position shown in Fig. 2. At this time the collar 22 can be moved longitudinally of the stand until its flared portion telescopes over and confines the upper ends of the legs 16. When in this position, the collar 22 cooperates with the slots 12 of the support 10 to prevent further rotative movement of the legs 16 relative to the central support 10, thus permitting the stand to be set upright.

Thereafter each of the arms 30, or as many as are needed, are raised vertically upward so that they telescope outwardly from the central support 10 of the stand, and then each of the arms 30 is rotated into the horizontal position shown in Fig. 2. Thereupon the rotatable head member 26 of the stand can be rotated relative to the central support 10 to bring each of the arms 30 adjacent the person placing materials on the arms of the stand. For example, if the stand is placed in a corner of a room, the rotatable head 26 can be used to permit loading of each arm and the rotation of the loaded arm away from the person doing the loading. Similarly the stand can be placed adjacent the ironing board and loaded or unloaded without moving the stand from its position on the floor.

The resilient disc 40 is so dimensioned that it bears against the edges of the arms 30 when those arms are telescoped within the support 10. By bearing against the edges of the outwardly projecting arms 30, the resilient disc 40 provides such a frictional force between the arms 30 and the head 26 and support 10 of the stand that although the stand is inverted the arms 30 will not slide out or otherwise telescope outwardly from the support 10. This makes the stand more readily handled by inexperienced persons and yet it does not in any way make it difficult for the user to extend the arms 30 outwardly from the central support 10. In addition, it prevents any shifting of the arms 30 relative to the head 26 or the support 10 and thus keeps the arms 30 from making noise. For these reasons, the present invention is even more desirable than the invention that is quite useful and has met wide acceptance and is disclosed in my co-pending application Serial No. 629,601.

Whereas the drawings and accompanying description have disclosed a preferred embodiment of the invention it is obvious to those skilled in the art that various changes may be made in the form or shape of the present invention without affecting the scope thereof.

What I claim is:

In a collapsible stand that comprises a central support, legs, a head member, and arms, the improvement which comprises a rotatable head member with a cylindrical recess in the underside thereof that can receive and telescope down-

wardly over the upper end of said central support, grooves and slots in said head member to receive said arms, a stop that is at the center of said head member and extends downwardly into said recess and is coextensive with the upper portions of said grooves, said arms having notches on the upper surfaces of the inner ends thereof which engage and are held against radially-directed inward movement by said stop 10 whenever said arms are in extended position, said arms having motion-limiting surfaces thereon which are spaced from said notches a distance less than one half the width of said central support, said motion-limiting surfaces being larger than said grooves to prevent radially-directed outward movement of said arms from said head member, and a resilient disc that is secured to said stop above the grooves and overlies just the inner portions of said slots and bears against the inner edges of the upper ends of the arms only when the arms are in housed position within the central support, said disc being compressible by the arms within the slots to clear said slots but being engageable with the upper ends of said arms to resist accidental movement of said arms relative to said slots and thus force the lower ends of said arms away from said central support.
